UNITED STATES PATENT OFFICE.

ELI A. GUTHMAN, OF NEW YORK, N. Y.

SAFETY-RAZOR.

1,146,701.

Specification of Letters Patent. Patented July 13, 1915.

Application filed February 14, 1914. Serial No. 818,694.

To all whom it may concern:

Be it known that I, ELI A. GUTHMAN, a citizen of the United States, and a resident of the city of New York, Bensonhurst, 5 borough of Brooklyn, in the county of Kings and State of New York, have invented a new and Improved Safety-Razor, of which the following is a full, clear, and exact description.

10 Among the principal objects which the present invention has in view are to amplify the available cutting edges of a razor of the character specified; to provide a holder adapted for rapid and ready adjustment of 15 the blades to place the various cutting edges in service position; to simplify the construction and arrangement of the holder and parts constituting the same; to simplify the individual blade-holders; and to provide a 20 construction the parts whereof are readily accessible for cleaning purposes.

In the drawings, Figure 1 is a section taken as on the line 1—1 in Fig. 7; Fig. 2 is a section taken as on the line 2—2 in Fig. 25 1; Fig. 3 is a view similar to Fig. 1, except that the blades and clamps therefor have been removed and the handle relaxed to spread the sides of the frame; Fig. 4 is a side view of the blade-holder and blade 30 shown as being revolved on the pivots of the holder, the frame being relaxed to permit the same; Fig. 5 is a detail view on an enlarged scale, in section, taken as on the line 5—5 in Fig. 4; Fig. 6 is a detail view 35 on an enlarged scale, in section, taken as on the line 6—6 in Fig. 1; Fig. 7 is an end view of a razor constructed and arranged in accordance with the present invention, the parts being shown in service relation; Fig. 40 8 is a longitudinal section taken as on the line 8—8 in Fig. 9, showing a modified form of the blade-holder and frame therefor; Fig. 9 is a flat side view of the same; Figs. 10 and 11 are detail views showing the separable coöperating plates forming the blade-holder 45 shown in Figs. 8 and 9; Fig. 12 is a flat face view, showing a modified form of the blade-holder and the blade disposed thereon.

50 As seen in the drawings, the blades 17 in the present invention are what are known as the "wafer" type, and are provided with two oppositely-disposed cutting edges. In the present invention, two such blades are 55 employed. Each of the blades is independ-

ently and primarily held in a separate holder. Each of the holders consists primarily of a cover plate 18 and a bed plate 19. The plates 18 and 19 are each provided with half-section pivot pintles 20, upon 60 which the holders revolve when locked up and when suitably mounted. Each bed plate 19 is provided with elongated alined bosses 21, and at one end of said plate are overhanging clips 22. Each cover plate 18 is 65 provided with slots 23, placed and formed to receive in coöperative relation said bosses 21, to therewith form guides for the sliding of the cover-plate over the blade 17 when held on the plate 19. The cover plate 18 is 70 similarly provided with clips 24, as best shown by the dotted lines in Fig. 4 of the drawings. When assembled, the clips 22 on the plates 19 are at opposite ends of the combined plates from the clips 24 on the plates 75 18. The clips 22 grip the end of the plate 18 in correspondence with the grip of the clips 24 on the plate 19.

To place the blades 17 in service, said blades are first adjusted upon the bed plate 80 19, perforations being provided in the blades to fit over the bosses 21, to therewith hold the blades against displacement. The cover plate 18 is then placed over the blade, the slots 23 of said plate being fitted over the 85 bosses 21. When the plate 18 is then moved so as to extend its free end under the clips 22, the clips 24 of said cover plate extend under, to hold the bed plate 19. In this position, the two half sections provided on 90 each of the plates coincide to form the pivot pintles 20. The blades are disposed in the holders, and said holders are handled independently, for adjustment in the holding frames. 95

The frame is constructed of relatively thin spring metal, having cheek pieces 25 and a cross piece 26. The cheek pieces 25 are each provided adjacent the upper edge thereof with inwardly-opening grooves 27. The grooves 27 in each cheek piece are disposed in angular relation, the angle being such as the needs of the construction, or the fancy of the designer dictates. The grooves 27 in the opposite cheek pieces coincide, said 100 grooves being provided to receive and hold the end lugs 28 with which the plates 18 and 19 are both provided. Centrally disposed in the grooves 27 are circular perforations 29, as best seen in Fig. 3 of the draw- 110

ings, through which the pintles 20 extend, said perforations forming bearings for said pintles.

The cheek pieces 25, as shown best in Fig. 4 of the drawings, are extended from the cross piece 26 at an angle of less than 90°. The cross piece 26, as illustrated in said figure of the drawings, is normally bowed upward between the cheek pieces, and is centrally perforated and provided with a tapped boss 30, the threads of which register with threads formed on the reduced end of a handle 31. As seen in Fig. 4 of the drawings, it is preferred that when the handle 31 is manipulated to relax the cross piece 26, the cheek pieces 25 are in position to receive and hold the pintles 20. In practice, it is required that the cheek pieces 25 be slightly spread to permit the introduction of the pintles 20 into the perforations 29. When the holders formed by the plates 18 and 19 are then swung on the pintles 20 to coincide the lugs 28 with the grooves 27, the natural spring of the cheek pieces 25 moves the groove-provided ends thereof to infold said lugs, to thereafter lightly maintain the holders and plates contained therein in service position.

The handle 31 is provided with a collar 32 to normally bear against the back of a rigid brace-plate 33. The plate 33 being rigid, when the handle 31 is manipulated, the boss 30 and center of the cross piece 26 are drawn toward the plate 33. This arrangement of the cross piece 26 increases the pressure of the cheek pieces 25 on the lugs 28 of the blade-holders, and serves to more rigidly maintain said holders in their service relation.

With a razor thus constructed, the operation is as follows: The blade-holders, if held between the cheek pieces 25, are removed therefrom by spreading the ends of said cheek pieces. The plates are moved relative to each other until the clips 22 and 24 become disengaged from the adjacent plates. The cover plates 18 are removed from the bed plates 19, and blades 17 are adjusted on the bed plates with reference to the bosses 21 thereon. The cover plates are then disposed over said blades in register with the bosses 21, and the two plates are then moved until the clips 22 and 24 engage the adjacent plates. The handle 31 and the cross piece 26 connected therewith being relaxed, the cheek pieces 25 are spread, to admit the pintles 20 to the perforations 29. The blade-holders are rotated until the lugs 28 register and pass within the grooves 27. The handle 31 is then manipulated to straighten the cross piece 26, and increase the tension of the cheek pieces 25 on the blade-holders. The razor is now in condition for use. If, during the employment of the razor, it be desired to present the edges of the blades 17

opposite to those which have been used, the handle 31 is manipulated to relax the tension of the cross piece 26 and the cheek pieces 25 sufficiently to permit the blade-holders to be rotated. The holders are then rotated to present the hitherto unused edges of the blades 17, when the holders are locked in operative position by manipulating the handle 31.

In Figs. 8 to 11 of the drawings, a modified form of the holder is shown. The modification consists in providing a cover plate 34, which is furnished with hook-like knuckle members 35 arranged to enfold and swing under and around the inset edges 36 of a bed plate 37, as shown best in Figs. 10 and 11 of the drawings. The cheek pieces 25, when used in conjunction with this modified form of the blade-holder, are provided with enlarged grooves to replace the grooves 27, said grooves being formed by hook-shaped edges 38 on said cheek pieces. In the modified form, the cover plate 34 swings lengthwise above the bed plate 37, and is provided with circular perforations 39, which register with the bosses 21, and do not slide relative thereto as in the preferred form of the invention. To hold the plate 34 in service relation to the bed plate 37 and blade when held therebetween, the bed plate 37 is provided with hook-shaped latches 40, under which the free end of the plate 34 snaps, when closed in service position, as shown best in Figs. 8 and 9. To lift the plate 34 from the service position, it is provided with a finger-clip 41, sufficiently raised from the exposed surface of the plate 34 to be engaged by the fingers of the operator, to draw the plate out of engagement with the latches 40. In operation, the modified form of the invention rotates about the pintles 42 with which the bed plate 37 only is provided.

The operation of the apparatus, when constructed in accordance with the modified form above described differs from the operation of the preferred form only in that the cover plate may be lifted to expose the cutting blade to permit its removal without disengaging the bed plate 37 from the cheek plates 25.

In Fig. 12 of the drawings, a further modification of the invention is shown, which consists in providing a base plate 43 with elongated plates 44 and a cross guard piece 45. The bed plate thus provided, as will be seen, permits the introduction of the blades 17 to service position, to be thereafter held by the spring tension of the clips 44. In this form of the invention, it will be noted that the cover plate as a separate element from the bed plate, is omitted.

I claim—

1. A razor as characterized, comprising a holding frame; and a plurality of blade-holders pivotally mounted in said frame in

operative position, said blade holders being rotatable therein to present successively the cutting edges of a blade held in said holders.

2. A razor as characterized, comprising a plurality of holders disposed in operative arrangement and pivotally mounted, each of said holders having finger-guards disposed at the opposite longitudinal edges thereof; a frame supporting said holders; and means for clamping said holders in relatively rigid service position.

3. A razor as characterized comprising, a frame having resilient cheek pieces; a plurality of blade holders rotatively mounted between said cheek pieces; and means for varying the tension of said cheek pieces.

4. A razor as characterized, comprising a frame having resilient cheek pieces; a double-edged cutting blade; a bed plate piv-

otally mounted in said cheek pieces and having a guard structure at one edge thereof for active disposition adjacent one edge of said blade; a cover plate shaped in correspondence with said bed plate and having a guard structure of similar character to guard the other edge of said blade when held between said bed plate and said cover plate; a handle mounted on said frame; and means embodied in said handle for varying the tension of said cheek pieces on said bed plate and said cover plate.

In testimony whereof I have signed my name to this specification in the presence of two subscribing witnesses.

ELI A. GUTHMAN.
